AIR CONDITIONING FRONT PANEL

Carl W. Sundberg, Bloomfield Hills, and Joseph A. Maxwell, Jr., Royal Oak, Mich., assignors to Whirlpool Corporation, a corporation of Delaware

Filed Apr. 3, 1961, Ser. No. 64,581

Term of patent 14 years

(Cl. D62—4)

FIGURE 1 is a front elevational view of the air conditioner front panel showing our new design.

FIGURE 2 is a sectional view taken substantially along line 2—2 of FIGURE 1.

FIGURE 3 is an enlarged, fragmentary perspective view of the upper left corner of the air conditioner front panel.

We claim:

The ornamental design for an air conditioner front panel, substantially as shown.
